UNITED STATES PATENT OFFICE.

LOUIS ROBINSON, OF LARNED, KANSAS.

SCREEN-WIRE RACK.

1,289,002.

Specification of Letters Patent. Patented Dec. 24, 1918.

Application filed June 26, 1917. Serial No. 177,125.

To all whom it may concern:

Be it known that I, LOUIS ROBINSON, a citizen of the United States, residing at Larned, in the county of Pawnee and State 5 of Kansas, have invented certain new and useful Improvements in Screen-Wire Racks, of which the following is a specification.

My invention relates to racks or stands for holding rolls of wire cloth or netting 10 for use in stores.

One of the objects of my invention is to provide a stand or rack and removable holders for the rolls of wire screen which will permit the screen of any desired length 15 to be unrolled without removal from the stand or if desired the holders may be removed from the rack and secured to the hooks on the measuring table so that the screen may be drawn over the table.

20 In the accompanying drawings, Figure 1 is a side elevation of a rack and measuring table embodying my invention; Fig. 2 is a side elevation of the same taken at right angles to the view shown in Fig. 1 and looking 25 in the direction of the arrow; Fig. 3 is an enlarged view of one of the detachable roll holders; Fig. 4 is a vertical sectional view on the line 4—4 of Fig. 3; and Fig. 5 is a partial side elevation of my rack having 30 the measuring table attached thereto.

The framework of the rack may be formed of angle irons, having a rectangular base 2, with upright members 3, secured to the corners of the base and inclined inwardly until 35 they join the intermediate rectangular frame 5, the front and rear members being then inclined toward each other at a greater angle and meeting at their upper ends, the two pairs being connected by a transverse 40 frame bar 6. The frame is rigidly braced by the diagonal brace rods 7. At either end the horizontal base member 2 and intermediate transverse frame member 5, are connected by a pair of auxiliary upright 45 members 8.

Each of the upright frame members 3 and 8, is provided with a series of hooks 10; the corresponding hooks upon opposite sides of the frame being at the same height and 50 constituting a pair of supports for one of the detachable roll holders.

The roll holders consist of pairs of spring or resilient metal loops or clips 12, having a central eye 12^a by which they are threaded 55 upon a supporting rod 14. It is obvious however that the spring clips may be se-

cured to the rod in any suitable manner. The ends of the rod 14 project beyond the 60 clips so that they may be hung in the hooks 10.

In securing the holders to the wire rolls 15, the clips 12 are sprung open slightly until they can be slipped over the ends of the rolls into a symmetrical position thereon as indicated. The roll is then suspended 65 upon the pair of hooks spaced a distance apart appropriate to the length of the roll, by resting the rod 14 in the hooks.

The screen wire may be drawn from any 70 roll by pulling it through the slots between the arms of the clip while the holder remains upon the hooks or the holder may be lifted from the hooks and hung upon the hooks 16, at the end of the measuring table 17, so that the screen wire may be pulled 75 out over the table before it is measured and cut. In Fig. 1, the table is shown separate from the rack and in Fig. 5 as secured to the uprights of the rack. In the latter case it is obvious that it may be detachably 80 secured thereto or hinged so that it may be folded for shipment or when not in use. In this form an adjacent pair of hooks on the uprights may support the holder so that the roll may rest upon the table in the manner 85 illustrated in Fig. 5.

The framework consisting of the truncated pyramidal lower part surmounted by the wedge-shaped upper part, constitutes a 90 very rigid stable structure, not easily overturned and furnishing a large surface area for the reception of the roll holders. The peculiar advantages derived from the detachable holders which may be readily shifted from the rack to the measuring table, 95 while maintaining the roll in compact condition will be especially appreciated by dealers in this class of merchandise. I have described in detail the particular construction 100 illustrated in the accompanying drawings for the purpose of clearly disclosing an embodiment of my invention, but it is to be understood that various changes and modifications may be made within the scope 105 of my claims and without departing from my invention.

I claim:—

1. In a wire cloth rack, wherein a frame is provided with upright members having a plurality of pairs of hooks secured thereto, a plurality of holders, each consisting of a pair of resilient loops or clips adapted 110

- to surround the rolls of material, and a rod connecting the clips and having its ends projecting outwardly therefrom to engage a pair of said hooks on the upright members.
- 5 2. In a wire cloth rack, wherein a frame is provided with upright members having a plurality of pairs of hooks secured thereto, a plurality of holders, each consisting of a pair of resilient loops or clips adapted to
- 10 surround the rolls of material, and having an eye at an intermediate point thereof, and a rod passing through the eyes and projecting outwardly therefrom to engage a pair of said hooks.
- 15 3. In a wire cloth rack, wherein a frame is provided with upright members having a plurality of horizontally aligned hooks, a measuring table portion having a pair of hook supports at one end thereof, and a
- 20 plurality of holders each consisting of a pair of loops or clips and a rod connecting the same, said rod being adapted to hang

interchangeably upon a pair of hooks upon said upright members or upon said hook supports on said table.

25

4. In a wire cloth rack, the combination of a frame provided with upright members having a plurality of horizontally aligned hooks, a horizontal platform adjacent said frame having a pair of upstanding hooks at one end thereof spaced apart a distance corresponding with the distance between the hooks on said frame, and a plurality of holders, each consisting of a plurality of resilient clips and a rod connecting the same, said holders being adapted to hang interchangeably upon a pair of hooks on said frame or upon the hooks on said platform.
